COOLING UNIT

Donald L. Spender, Waterbury, Conn., assignor
to Scovill Manufacturing Company, Waterbury,
Conn., a corporation of Connecticut

Application March 11, 1944, Serial No. 526,111

11 Claims. (Cl. 257—263)

1

This invention relates to cooling or heat exchange units or devices through which air is circulated as a cooling medium. More particularly, the invention relates to units or devices of this class constructed of a plurality of similar blades or vanes assembled to form the unit, and still more particularly wherein means is provided on the blades for circulating air radially through the outer wall portion of the unit as well as longitudinally through the unit. The novel features of the invention will be best understood from the following description when taken together with the accompanying drawing in which certain embodiments of the invention are disclosed, and in which the separate parts are designated by suitable reference characters in each of the views, and in which:

Fig. 1 is a side view of a unit made according to my invention and diagrammatically indicating in dot and dash lines one adaptation and use of the invention.

Fig. 2 is a partial section on the line 2—2 of Fig. 1 on an enlarged scale.

Fig. 3 is an enlarged perspective view of one of the blades or vanes employed in constructing the complete unit, as seen in Figs. 1 and 2.

Fig. 4 is a partial longitudinal section through the outer flange of the blade, showing a modification.

Fig. 5 is a side view of the outer wall portion only of a modified form of unit and showing only a part thereof; and

Fig. 6 is a partial section on the line 6—6 of Fig. 5.

This application constitutes a continuation in part of the cooling unit as disclosed in my prior application Serial Number 524,831, filed March 1, 1944, in which application the general adaptation and use of units of the kind under consideration has been specifically dealt with. The present application deals specifically with the provision of a blade structure having means providing for radial as well as longitudinal circulation of air through the unit to thereby produce more effective and efficient cooling of the unit as and when greater efficiency in cooling is required.

In illustrating one use of the unit, I have diagrammatically illustrated in dot and dash lines in Fig. 1 of the drawing at 10 a radio tube or other electric discharge device upon the anode 11 of which is supported one of my improved cooling units 12. At 13 is shown an electric contact engaging the outer wall at one end portion of the unit. It will, of course, be apparent that cooling

2

or heat radiating units of the type and kind herein disclosed may be used for many other purposes, and may be of any desired size and structural form.

5 In constructing the unit, a plurality of similar blades or vanes 14 are employed, one of these blades is shown in perspective detail in Fig. 3 of the drawing. The blade comprises an elongated body portion 15 terminating in inner and outer flanges 16 and 17. The flange 16 extends in the direction of one side surface of the body 15, and comprises an inner part 18 and an offset outer part 19 offset outwardly with respect to the part 18. This construction forms an interfitting between the blades or vanes in forming the inner tubular wall portion 20 of the unit, as seen in Fig. 2 of the drawing.

The outer wall portion 21 of the unit is formed from the flanges 17. These flanges have a wide 20 central portion 22, one edge of which joins the body 15 in a rounded bead 23 and at the other edge is a curved or hook shaped flange portion 24. The center portion 22 has longitudinally spaced elongated vent apertures 25 which form 25 on the resulting outer wall 21 circumferentially spaced passages through which air blown into the chambers 26 between adjacent blades can be discharged radially, as will be apparent. In some uses of devices of the kind under consideration, 30 a fan or blower is employed to pass the air in at least one direction to the passages 26. However, in other uses, a normal circulation of air will be generated, and in this latter instance, air will be drawn into the unit through both ends thereof. 35 In these last uses, the unit may be employed as a heat radiating medium, device or apparatus.

In interfitting and interlocking the blades or vanes 14, the hook shaped flanges 24 of one blade will interlock with the bead 23 of an adjacent blade, leaving the apertures 25 freely exposed through the outer wall portion 21, as will clearly appear from a consideration of Fig. 2 of the drawing. It will be understood that any means may be provided to securely retain the 45 blades against lateral shifting or separation. In some instances, the blades may be welded, brazed or soldered together to form the unit.

In Fig. 4 of the drawing is shown a slight modification in the structure of the outer flange of a 50 blade, that is to say, a flange similar to the flange 17 of a blade similar to the blade 14. This figure shows a longitudinal section through a part 22a of a flange which would be similar to the flat central portion 22. Instead of having spaced elongated apertures as at 25, the flange will have

spaced smaller apertures 27, and this flange in alignment with the apertures will have inwardly extending baffles or deflector plates 28 formed from the material of the flange and in the formation of the apertures 27. In Fig. 4 is illustrated at 15a, part of the body portion of the blade similar to the body portion 15, and at 23a is shown part of the bead similar to the bead 23. The deflectors or baffles 28 extend into the unit or into chambers similar to the chambers 26, and with units employing blades of the kind partially illustrated in Fig. 4 of the drawing, air will preferably be circulated through the unit in the direction of the arrow 29. It will thus appear that the baffles 28 will serve to pick-up and deflect a forced draft of air outwardly through the periphery of the unit.

In Figs. 5 and 6 of the drawing is shown another adaptation of the invention. In this construction, blades 30 will be employed having inner ends similar to the flanged ends 16 of the blades 14, but instead of having outer flanges running the full length of the blades, the same as the flanges 17, the blades 30 will have at their outer ends short flanges 31. The flanges 31 will have beads 32 similar to the beads 23, and instead of the flat portions 22, will have inwardly beaded portions 33 and hook shaped end flanges 34 which are coupled similar to the flanges 24, forming large openings extending the full length of the blades at the outer part of the unit, as will clearly appear from a consideration of Fig. 5 of the drawing. In other words, with this construction, a free circulation of air is provided not only longitudinally, but radially through the unit from chambers 35 similar to the chambers 26, and this circulation is obstructed only insofar as the coupling flanges 31 are concerned.

In order to retain the blades 30 against displacement and shifting, the same are further interlocked, for example, by providing apertures 36 in the beads 32 and inwardly projecting knobs 37 on the hook shaped flanges 34 adapted to enter the apertures 36 on the beads 32 of an adjacent blade. However, other means of securing the blades together can be employed.

Having fully described my invention, what I claim as new and desire to secure by Letters Patent is:

1. A cooling unit for electric discharge devices of the class described, said unit comprising a plurality of similar blades, each blade having an offset flange at side portions thereof, the flange of common sides of the blades overlapping and interfitting one with the other to form inner and outer tubular wall portions on said unit, the blades having body portions extending radially between and spacing said inner and outer wall portions, said blades forming spaced circulating passages extending longitudinally through said unit, and at least one of said wall portions having circumferentially spaced apertures to provide circulation from said passages through said wall portion.

2. A cooling unit for electric discharge devices of the class described, said unit comprising a plurality of similar blades, each blade having an offset flange at side portions thereof, the flange of common sides of the blades overlapping and interfitting one with the other to form inner and outer tubular wall portions on said unit, the blades having body portions extending radially between and spacing said inner and outer wall portions, said blades forming spaced circulating passages extending longitudinally through said unit, at least one of said wall portions having circum-

ferentially spaced apertures to provide circulation from said passages through said wall portion, and said wall portion having means extending into the circulating passages for directing circulation through said apertures.

3. A cooling unit for electric discharge devices of the class described, said unit comprising a plurality of similar blades, each blade having an offset flange at side portions thereof, the flange of common sides of the blades overlapping and interfitting one with the other to form inner and outer tubular wall portions on said unit, the blades having body portions extending radially between and spacing said inner and outer wall portions, said blades forming spaced circulating passages extending longitudinally through said unit, and the outer tubular wall portion occupying only a portion of the length of said blades forming large circulating passages between outer ends of the blades communicating with the circulating passages extending longitudinally through the unit.

4. A cooling unit for electric discharge devices of the class described, said unit comprising a plurality of similar blades, each blade having an offset flange at side portions thereof, the flange of common sides of the blades overlapping and interfitting one with the other to form inner and outer tubular wall portions on said unit, the blades having body portions extending radially between and spacing said inner and outer wall portions, said blades forming spaced circulating passages extending longitudinally through said unit, the outer tubular wall portion occupying only a portion of the length of said blades forming large circulating passages between outer ends of the blades communicating with the circulating passages extending longitudinally through the unit, and means on the offset flanges forming the outer wall portion for interlocking said flanges in retaining the blades against displacement one from the other.

5. A cooling unit for electric discharge devices of the class described, said unit comprising a plurality of similar blades, each blade having an offset flange at side portions thereof, the flange of common sides of the blades overlapping and interfitting one with the other to form inner and outer tubular wall portions on said unit, the blades having body portions extending radially between and spacing said inner and outer wall portions, said blades forming spaced circulating passages extending longitudinally through said unit, and the offset flanges forming the outer wall portion of said unit having longitudinally spaced apertures communicating with said circulating passages.

6. A cooling unit for electric discharge devices of the class described, said unit comprising a plurality of similar blades, each blade having an offset flange at side portions thereof, the flange of common sides of the blades overlapping and interfitting one with the other to form inner and outer tubular wall portions on said unit, the blades having body portions extending radially between and spacing said inner and outer wall portions, said blades forming spaced circulating passages extending longitudinally through said unit, the offset flanges forming the outer wall portion of said unit having longitudinally spaced apertures communicating with said circulating passages, and said last named flanges having baffle portions extending into the circulating passages adjacent said apertures for directing circulation through said apertures.

7. A blade for producing devices of the class described, by assemblage of a plurality of such blades, said blade comprising a body portion of predetermined length and width, opposed edges of said body portion having angularly extending flanges, the flange at one edge of the body portion extending in the direction of one side surface of the body portion and the flange at the other edge in the direction of the opposite surface of said body portion, the flange at one edge portion of the blade extending the full length thereof, and the flange at the other edge portion of the blade extending only throughout part of the length of the blade forming at said edge portion of the blade longitudinally spaced apertures.

8. A blade for producing devices of the class described, by assemblage of a plurality of such blades, said blade comprising a body portion of predetermined length and width, opposed edges of said body portion having angularly extending flanges, the flange at one edge of the body portion extending in the direction of one side surface of the body portion and the flange at the other edge in the direction of the opposite surface of said body portion, the flange at one edge portion of the blade extending the full length thereof, the flange at the other edge portion of the blade extending only throughout part of the length of the blade forming at said edge portion of the blade longitudinally spaced apertures, and said blade having baffles adjacent said apertures and extending angularly with respect to said flange.

9. A blade for producing devices of the class described, by assemblage of a plurality of such blades, said blade comprising a body portion of predetermined length and width, opposed edges of said body portion having angularly extending flanges, the flange at one edge of the body portion extending in the direction of one side surface of the body portion and the flange at the other edge in the direction of the opposite surface of said body portion, the flange at one edge portion of the blade extending the full length thereof, the flange at the other edge portion of the blade extending only throughout part of the length of the blade forming at said edge portion of the blade longitudinally spaced apertures, and the flange at one edge portion of the blade being hook-shaped in cross section for coupling engagement with an adjacent blade of an assemblage in producing said device.

10. A device of the character described, said device comprising an assemblage of substantially similar blades, flanges at opposed side edge portions of the blades, said flanges having offset por-

tions overlapping and interfitting with adjacent blades in forming an assembled unit with circulating passages between adjacent blades within said flanges, one of the flanges of each of said blades having a wide central portion extending longitudinally of the blade and joining the body portion of the blade in a rounded bead, a hook shaped portion integral with the other side of said central portion adapted to engage the bead of an adjacent blade in coupling the blades together in forming said unit, leaving a part of said flange exposed intermediate said bead and hook shaped portions, and said exposed part of the flange of each blade having an aperture therein communicating with said circulating passages.

11. A blade for producing cooling units by an assemblage of a plurality of said blades, said blades comprising an elongated body portion, opposed edges of the body portion having angularly extending flanges, the flange at one edge of the body portion extending in the direction of one side surface of the body portion and the flange at the other edge in the direction of the opposite surface of said body portion, one of said flanges joining the body portion in an outwardly extending bead arranged longitudinally of the blade, the free end of said last named flange terminating in an elongated curved portion of hook shaped cross sectional form, said bead and hook shaped portion being joined by a wide inwardly set part of the flange, and said inwardly set part of the flange having longitudinally spaced apertures.
